UNITED STATES PATENT OFFICE

98,123

DESIGN FOR A CASE FOR CALCULATING MACHINES

Walter W. Landsiedel, Norwood, Ohio, assignor to Remington Rand Inc., New York, N. Y., a corporation of Delaware

Application October 10, 1935, Serial No. 58,933

Term of patent 7 years

To all whom it may concern:

Be it known that I, Walter W. Landsiedel, a citizen of the United States, residing in Norwood, in the county of Hamilton and State of Ohio, have invented a new, original, and ornamental Design for a Case for Calculating Machines, of which the following is a specification, reference being had to the accompanying drawing forming a part thereof.

Fig. 1 is a perspective view of a case for a calculating machine embodying my design, the

view showing the case as seen from the upper front right hand side thereof.

Fig. 2 is a perspective view of the same as seen from the upper, rear, left hand side thereof.

Fig. 3 is a side elevational view of the same.

I claim:

The ornamental design for a case for calculating machines as shown and described.

Signed at Norwood in the county of Hamilton and State of Ohio this 4th day of October, 1935.

WALTER W. LANDSIEDEL.
